2

Des. 906

To all whom it may concern:

Be it known that I, Elias Young, of Cincinnati in the County of Hamilton and State of Ohio, have invented or produced a new and original design for a Cooking Stove, and I hereby declare ..... the accompanying drawings (which are made a part of this specification) to form a full, clear, and exact delineation of the same:—

Ex. 2

S. M. P.

Fig. 1. being a perspective view of the stove, and

Fig. 2. a vertical longitudinal section of the front part thereof.

I claim as new and of my invention the ornamental design of Cooking Stove substantially as herein Exhibited.

In testimony of which Invention I hereunto set my hand.
